UNITED STATES PATENT OFFICE.

GILBERT W. GOODRIDGE, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

SWITCH-HANDLE.

1,072,224.

Specification of Letters Patent.

Patented Sept. 2, 1913.

Application filed December 1, 1911. Serial No. 663,245.

To all whom it may concern:

Be it known that I, GILBERT W. GOODRIDGE, a citizen of the United States of America, residing in the city of Bridgeport, 5 in the county of Fairfield, in the State of Connecticut, have invented certain new and useful Improvements in Switch-Handles, of which the following is a specification.

My invention relates to switch handles, 10 and particularly to a metallic handle for electric snap switches, the object of my invention being to provide a metallic switch handle of simple construction adapted for use on switches of this character.

15 In the accompanying drawing, Figure 1 is a dropped vertical section through the switch handle parts; Fig. 2 is a dropped plan view of the same; Fig. 3 is a vertical section through the parts assembled; and 20 Fig. 4 is a side elevation of a switch handle.

The commonly employed switch handle for rotary snap switches is made of vulcanite or other insulating substance, which is secured in any suitable way upon the upper end of the switch spindle. These vulcanite handles are difficult to mold without flaws entering into their composition, and even when perfectly made are of a 25 more or less frangible nature, with the result that there is frequent breakage, rendering the switch useless until the defective handle has been replaced.

The present handle is designed to be made entirely of metal to avoid the difficulties 35 above pointed out. The construction illustrated comprises a winged shell 5, forming the thumb piece, which is offset adjacent its lower edge to form a shoulder 6 against which a closure diaphragm 7 is seated and 40 held in place by rolling over the lower edge of the shell 5, as illustrated in Fig. 3. A central aperture 8 in the diaphragm is provided to permit the passage therethrough of the stem 9 of the T-piece 10 which is provided 45 with wings 11 working in the wings 12 of the thumb piece 5, thus giving freedom for a limited vertical displacement of the thumb piece with relation to the T-piece,

while insuring their rotary relation. The T-piece 10 is frequently threaded at 13 to 50 receive the threaded end 14 of the usual switch spindle. A coiled spring 15 surrounds the shank of the T-piece 9 and bears at its upper end against the head of the latter and at its lower end against the 55 thimble 16, of the closure diaphragm 7.

To facilitate the finishing of the handle, the diaphragm 7 is provided with apertures 17, which form vents and discharge openings through which any substances entering the interior of the handle during the finishing operation may be discharged.

To assemble the parts, the T-piece with the coiled spring 15 in position upon the shank 9 thereof, is inserted within the shell 65 of the thumb key, and the closure diaphragm positioned over the shank 9 and rested against the shoulder 6. In this position the lower edge of the shell is rolled over to secure the diaphragm in position. Inasmuch 70 as the shank 9 is free to pass through the central aperture 8 in the closure disk, the T-piece which is mounted upon the switch spindle is free to be drawn down within the handle by the switch mechanism in a 75 manner well understood by those familiar with the art.

I claim as my invention,

A switch handle comprising a metallic shell having wings 12 and having its side 80 walls recessed at their lower edges, a closure diaphragm normally seated against said recesses, a threaded stem passing through said diaphragm, a head for said stem shaped substantially to the inner contour of said 85 winged shell, in combination with a spring surrounding said stem and engaged between said head and closure diaphragm, substantially as described.

In testimony whereof I have signed my 90 name to this specification, in the presence of two subscribing witnesses.

GILBERT W. GOODRIDGE.
